R. H. MORTON

BOWLING GAME APPARATUS

Filed Dec. 22, 1926

Inventor:
Ralph H. Morton,
by Arthur F. Randall,
Atty.

UNITED STATES PATENT OFFICE.

RALPH H. MORTON, OF WEYMOUTH, MASSACHUSETTS.

BOWLING GAME APPARATUS.

Application filed December 22, 1926. Serial No. 156,454.

My invention relates to games and particularly to bowling game apparatus, the object of my invention being to provide an improved bowling game apparatus of simple and attractive construction which may be used in a parlor or the like to practice an interesting and entertaining game of bowling calling for skill on the part of the player or players. It is also an object of the invention to provide an apparatus of the character described which may be used within the parlor or other room of a house without injury to the walls of the room or to the furniture within the latter.

To these ends I have provided an improved bowling game apparatus having the peculiar features of construction set forth in the following description, the novel features of the invention being particularly pointed out and defined in the claims at the close thereof.

In the accompanying drawings:

Figure 1 is a plan view of the target structure of my improved bowling game apparatus.

Figure 2 is a front elevation of the target structure shown in Fig. 1.

Figure 3 is a side elevation of the target structure shown in Figs. 1 and 2.

Figures 4 and 5 illustrate one form of projectile constituting a part of my improved apparatus.

My improved game apparatus includes a target structure comprising two vertical side walls 1, 1. To each of these side walls 1 is secured, by means of screws 2, an upright post 3, said post being disposed adjacent the forward or front ends of the upright walls 1. At their upper ends the posts 3 are provided with holes through which extend the opposite threaded end portion of a crossbar 4 herein shown as a round metal rod having mounted thereon two nuts 5, 5, one near each end of said rod. Thumb nuts 6 mounted upon the outer end portions of the rod 4 clamp the upper ends of the posts 3 against the nuts 5. Pivoted loosely on the cross-bar or rod 4 is a row or series of targets 7 yieldingly held in vertical positions with provision for rotary movement on the rod 4 by any suitable means. As herein shown these targets 7 are strips of wood each formed with a transverse hole through it to receive the rod 4, said hole being nearer one end of the strip than the other so that

gravity acting upon the heavier end holds the target in its normal vertical position.

The targets 7 are maintained spaced apart relatively and positioned properly with relation to the side walls 1, 1 by means of sleeves 8 arranged between the targets 7 and at each end of the series. It will be seen that the cross-bar 4 serves two purposes, viz, as the pivotal support for the targets 7 and also as means for connecting the forward ends of the two side walls and supporting the latter in vertical positions.

Near their rear ends the side walls 1, 1 are formed with sockets or holes to receive trunnions 9 provided at the opposite ends of a cross-bar 10. This cross-bar serves as a connector for the rear ends of the side walls 1, 1 and assists the pivot bar 4 in maintaining the side walls in vertical positions. Its main function, however, is to effect the re-bound of the projectile constituting part of the apparatus. One form of projectile is illustrated in Figs. 4 and 5 and this form consists of a disk 11 of wood or the like made with an annular peripheral groove within 80 which is seated an annular rubber tire 12.

The game apparatus is used by placing the target structure shown in Fig. 1 upon the floor near one side of the room, or at the end of a hallway, with the targets facing the opposite side of the room, or the opposite end of the hallway. The player then rolls the disk 11 toward the target structure so as to enter between the side walls 1. The disk thus thrown or rolled toward the target structure either passes between or strikes one or more of the targets 7 beyond which it passes to the cross-bar 10. This cross-bar 10 is positioned vertically from the floor a distance approximately equal to one-half the diameter of the disk 11 so that said cross-bar serves as a stop to prevent the disk from passing beyond the side walls and striking the wall of the room. The main function of the cross-bar, as stated, is to cause the disk projectile to re-bound and the game is played with the object in view not only of scoring a hit on the direct throw of the projectile but with the object in view of causing the projectile to re-bound and again strike one or more of the targets so that a skillful player can score two hits on a throw. In practice I prefer to make the cross-bar 10 as a resilient strip of wood which is flexed by the impact of the projectile so that 110

it will throw the latter back against the targets if the projectile is skillfully handled.

The targets may be numbered upon both sides, front and rear, so that the score is 5 computed by the number, or numbers on the target, or targets, struck by the projectile as it passes into the target structure and upon its re-bound.

The bottom edge of each side wall, which 10 is constituted by a shoe 13 of rubber or the like, serves the double purpose of protecting the floor of the room in which the apparatus is used and also to provide a frictional engagement between the side walls 15 and the floor serving to hold the target apparatus against accidental displacement.

What I claim is:

1. A bowling game apparatus comprising a target structure consisting of two upstanding side walls; a cross-bar adjacent the forward ends of said side walls supported at its ends by the latter in an elevated position; a series of separate targets rotatably mounted on said cross-bar and held in vertical position 25 by gravity; a projectile adapted to be propelled over the floor or ground in a direction to enter between said side walls so as to pass under or adjacent said targets, and a rear spring cross-bar supported at its ends in a 30 horizontal position by said side walls near the rear ends of the latter; said spring cross-bar occupying a position in the path of the projectile after the latter passes the targets and operating, when struck by a projectile, 35 to throw the latter back against the targets.

2. A bowling game apparatus constructed in accordance with claim 1 and wherein the front cross-bar is a round rod having target spacing and positioning members mounted thereon between the targets and at each end 40 of the series of targets, and nuts on said cross-bar for holding said side walls, spacing members spring cross-bar and the targets in assembled relationship.

3. A bowling game apparatus comprising 45 a target structure consisting of two upstanding side walls; a cross-bar adjacent the forward ends of said side walls and extending through the latter; means separably fastening said side walls to said cross-bar whereby 50 they are held against movement on said bar toward and from each other; a series of separate targets pivotally mounted on said cross-bar and held in vertical positions by 55 gravity but freely rotatable on said bar in either direction; sleeves mounted on said cross-bar for holding said targets in spaced relationship; a disk projectile adapted to be rolled over the floor or ground in a direction to enter between said side walls so as 60 to pass under or adjacent said targets, and a resilient cross-bar adjacent the rear ends of said side walls having end trunnions removably fitted in sockets provided in said side walls, said resilient cross-bar being in 65 the path of the projectile after it passes the targets and when struck by the projectile being flexed by the latter so as to throw the projectile back against the targets.

RALPH H. MORTON.
